UNITED STATES PATENT OFFICE.

HENRY GRUESSER, OF CINCINNATI, OHIO, ASSIGNOR TO THE EMERY CANDLE COMPANY, OF CINCINNATI, OHIO, A CORPORATION OF OHIO.

DESIGN FOR A CANDLE.

Application filed March 11, 1922. Serial No. 1,127. Term of patent 7 years.

To all whom it may concern:

Be it known that I, HENRY GRUESSER, a citizen of the United States, residing at Cincinnati, in the county of Hamilton and State of Ohio, have invented a new, original, and ornamental Design for a Candle, of which the following is a specification, reference being had to the accompanying drawings, forming a part thereof.

Fig. 2 is an enlarged top plan view.

Fig. 3 is an enlarged bottom plan view.

I claim:

The ornamental design for a candle, as shown.

HENRY GRUESSER.
